UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

HINGE CONSTRUCTION FOR DECK LIDS.

Application filed September 29, 1924. Serial No. 740,578.

This invention relates generally to hinge construction and refers more particularly to those designed for deck lids of vehicle bodies.

5 An object of the invention is to provide a strong and durable hinge of this type which preferably has means for reinforcing and bracing the deck lid.

Another object is to provide suitable 10 counter-balancing means for the deck lid so as to facilitate the upward movement thereof.

With the above and other objects in view, the invention consists of certain novel features of construction, combinations and arrangements of parts as will be more fully described and particularly pointed out in the appended claims.

In the accompanying drawing;—

20 Figure 1 is a fragmentary side elevation of a vehicle body embodying my invention;

Figure 2 is a sectional view taken on line 2—2 of Figure 1;

25 Figure 3 is a fragmentary sectional view through the deck and deck-lid;

Figure 4 is a vertical sectional view through the deck lid, hinge and a portion of the vehicle frame-work;

30 Figure 5 is a detail perspective view of one of the hinges.

Referring now to the drawing in which like characters of reference designate corresponding parts throughout the several views, the numeral 1 designates a vehicle 35 body of the closed type having the usual compartment 2 below the deck 3 at the rear end thereof for carrying luggage or other articles.

40 A metallic lid 4 is preferably used to close the opening 5 in the deck and is preferably connected to the usual wooden frame 6 of the body by means of a pair of hinges 7 that are pivoted upon horizontal pins or studs 8 carried by integral projections 9 of the rear 45 panel 10.

Each hinge 7 is preferably formed from sheet metal and the apertured body portion 11 thereof is preferably provided with an elongated lateral extension 12 that is preferably L-shape in cross-section and that is 50 preferably secured to the lower face of the lid 4, while projecting forwardly from the extension 12 adjacent to the body portion 11 is an elongated extension 13 which is preferably parallel to the body portion 11 and

which is preferably secured to a depending flange 14 at one side of the lid 4. Thus, each hinge serves as a brace for the deck-lid and materially reinforces the same.

The metal lid 4 is quite heavy and to facilitate the movement thereof, I preferably provide one or more counter-balancing springs 15. The single spring shown is preferably connected at one end to a depending flange 16 at the forward end of the deck-lid and is connected at the other end to the inner side of one of the usual wheel guards 17. Thus this spring will effectively balance the weight of the deck-lid.

For cushioning the lid, I preferably provide suitable resilient knobs 18 which are preferably secured to blocks 19 attached to the lower face of the lid 4 and which are adapted to engage suitable blocks 20, preferably of wood that are secured to the wheel guards 17. The blocks 19 are preferably located at the rear corners of the lid and serve as reinforcing members for the side and rear flanges 14 and 21 respectively.

While it is believed that from the foregoing description, the nature and advantages of the invention will be readily apparent I desire to have it understood that I do not limit myself to what is herein shown and described and that such changes may be resorted to when desired as fall within the scope of what is claimed.

What I claim as my invention is:

1. The combination with a deck having an opening, of a closure for the opening having a depending flange, and a connection between the deck and closure including a hinge member having a body portion pivotally connected to the deck and having diverging extensions secured respectively to said closure and flange.

2. The combination with a deck having an opening, of a closure for the opening having a depending flange, means for pivotally connecting the closure to the deck including a hinge member having a body portion pivotally connected to the deck and having extensions projecting at substantially right angles to each other secured respectively to said closure and flange.

3. In a vehicle body, the combination with a deck having an opening, of a closure for said opening having a depending flange, a connection between the deck and closure including a hinge member formed from a

single piece of material having an intermediate body portion pivotally connected to the deck and having a lateral extension secured to said closure, and a second extension spaced below and extending at right angles to the extension aforesaid secured to the depending flange.

4. In a vehicle body, the combination with a deck having an opening, of a closure for said opening having a depending flange, a connection between the deck and closure including a pin carried by the deck, a hinge member having a body portion pivoted on the pin and having diverging extensions, one of said extensions projecting at right angles to the body portion and having a lateral flange secured to the closure, and a second extension disposed below and substantially parallel with the body portion secured to the depending flange.

5. The combination with a deck having an opening therein, of a closure for the opening having a depending flange, a pin projecting from the deck, means for pivotal-

ly connecting the closure to the deck including a hinge member having a body portion pivoted on said pin, an extension projecting laterally from said body portion secured to said closure and an extension secured to the flange aforesaid.

6. A hinge member formed from a single sheet of metal comprising an apertured body portion having a lateral extension, and an extension positioned substantially below and extending in the same direction parallel to said body portion and disposed at right angles to the lateral extension.

7. A hinge member formed from a single sheet of metal comprising an apertured body portion having an elongated L-shaped lateral extension, and an elongated extension positioned adjacent to and extending in the same direction as said body portion and disposed substantially below and at right angles to the lateral extension.

In testimony whereof I affix my signature.

HERMAN C. MAISE.
